Primary Examiner—Jeffrey Asch*Attorney, Agent, or Firm*—Perman & Green, LLP**CLAIM**

The ornamental design for a “key array for a handset”, as shown and described.

DESCRIPTION

FIG. 1 is a front, bottom, right side perspective view of a key array for a handset, showing our new design;

FIG. 2 is a front elevational view thereof; and,

FIG. 3 is a top, left side, front perspective view thereof.

The broken lines showing an outline of the handset is for illustration purposes only and forms no part of the claimed invention.
